UNITED STATES PATENT OFFICE

2,312,162

MANUFACTURE OF DRY-SEALING
ENVELOPES

Vincent E. Heywood, Worcester, Mass., assignor
to United States Envelope Company, Spring-
field, Mass., a corporation of Maine

Application July 15, 1940, Serial No. 345,530

20 Claims. (Cl. 93—62)

The present invention relates to the manufacture of envelopes of the dry-sealing type, i. e., envelopes characterized by the application of dry-sealing adhesive to corresponding areas or portions that are foldable into overlying relation in a completed envelope for sealing upon contact.

In the manufacture of dry-sealing envelopes, certain problems arise, owing to inherent characteristics of liquid dry-sealing adhesive which make it difficult to apply to envelope material without overrunning the limits of the areas of its application. Furthermore, provision must be made for drying the applications of adhesive to the envelope material while maintaining the adhesive coated areas out of engagement with each other.

Owing to the difficulty of applying dry-sealing adhesive by the use of gumming dies usually employed in envelope machinery, it has heretofore been proposed to apply the adhesive with a wiping action to blanks arranged in stepped relation, for example, as shown in Winkler and Dunnebier Patent No. 2,019,946, issued November 5, 1935. However, when dry-sealing adhesive is so applied to the exposed edges of blanks arranged in stepped relation, special provision must be made for separating the blanks to prevent adhesion to each other along their edges, and such separation always involves the possibility of the adhesive stringing out, as separate coatings are pulled apart.

According to the present invention, the problems involved in the application of dry-sealing adhesive to different and separated areas of envelope blanks, are successfully solved by utilizing the movements of a blank in different planes to successively apply the adhesive with a wiping action to the different trailing edges of the blank. Following the separate applications of adhesive to each blank, blanks assembled in offset relation are subjected to a drying action from opposite sides, with the separate adhesive areas positively maintained in spaced relation, so that the possibility of stringing or edge sticking of adjacent blanks is entirely eliminated.

The above and other advantageous features of the invention will hereinafter more fully appear from the following description, with reference to the accompanying drawings, in which:

Fig. 1 is a view in side elevation of apparatus for carrying out the invention, with some parts in sections.

Fig. 2 is a view in front elevation of the parts shown in Fig. 1.

Fig. 3 is a fragmentary plan view, on an enlarged scale, illustrating the positioning of a blank at an adhesive applying station.

Fig. 4 is a fragmentary view partly in section, along the line 4—4 of Fig. 3, and partly in elevation.

Figs. 5, 6 and 7 are views similar to Fig. 4, showing the parts in different positions.

Fig. 8 is a plan view of the overlapped blanks 10 shown in Fig. 7, as supported on the conveyor for drying.

Fig. 9 is a fragmentary plan view of an adhesive applying bar and its associated blank stripers.

15 Fig. 10 is a sectional view of the bar of Fig. 9, on an enlarged scale.

Fig. 11 is a plan view of the conveyor shown in Fig. 1, with other parts removed.

20 Fig. 12 is a sectional view along the line 12—12 of Fig. 11 looking in the direction of the arrows.

Fig. 13 is a fragmentary sectional view along the line 13—13 of Fig. 12, looking in the direction of the arrows.

25 Fig. 14 is a fragmentary and partly diagrammatic view illustrating the timing of the mechanism.

Referring first to Figs. 1 and 2, the apparatus consists of spaced side frame members 1, between which is supported a stack of flat blanks 30 2, by means of pairs of posts 3 and 4 engaging in corners formed at the side flaps 2a of the stacked blanks. The lower posts 3 are carried by holders 5, longitudinally adjustable on brackets 6, while the brackets 6 are adjustable on slides 7 carried by the frame members 1 at right angles to the holders 5.

Consequently, the posts 3 can be adjusted in two directions, so as to fit into the corners of different sizes of blanks, as indicated in dotted lines. The upper posts 4 are carried by holders 8 adjustable in one direction on a cross member 9, so that the posts 4 can be adjusted to blank stacks of different widths, with the upper edge of the stack always centered with respect to a stop 10 extending slightly beneath the lowermost blank, as shown in Fig. 1. The lower ends of the posts 3 terminate in stops 11, slightly underlying opposite corners of the stack, and followers 12 slidably mounted on the posts 3 above the stack, 40 exert a pressure tending to feed the stack toward the stops 11, by reason of the connection of the inside of the posts 3 to a source of suction.

With the arrangement of parts described thus far, it is evident that the stack of blanks is supported at three points by the stops 10 and 11, with

almost the entire under surface of the lowermost blank free, except where its entire lower edge rests in contact with an adhesive supplying bar 13. A bracket 14 supports the bar 13, the bracket being adjustable in one slide 7, so that a trough 15 in the bar 13 can be adjusted so as to underlie the edge of the stack by an appreciable distance, as shown in Fig. 1, and as indicated by dotted lines in Fig. 2. The effective length of the trough 15 is adapted to be controlled by end lugs 16, adjustable within the trough so as to extend slightly within the margins of a blank, as also shown in Fig. 3.

The bar 13 also provides a narrow slit 17 disposed between the edge of the blank and the trough 15, and this slit communicates with a chamber 18 running the entire length of the trough 15, and connected to a suitable source of suction. When suction is applied to the lowermost blank through the slit 17, the entire edge portion of the blank is held flat against the bar, so that the blank makes a tight seal with the edges of the trough 15 between the end lugs 16. Consequently, when dry-sealing adhesive in liquid form is supplied to the trough 15 through a suitable supply pipe 19, the adhesive engages the lowermost blank along a zone slightly displaced from the lower edge of the blank. The suction applied to the blank through the slit 17 adjacent the trough, is sufficient, however, to prevent leakage of the adhesive therefrom.

As best shown in Fig. 1, a suction picker 20 is mounted to turn with a shaft 21, and its free end is adapted to engage the upper edge of the lowermost blank adjacent the stop 10. When suction is applied to the picker 20 and the latter is swung into the dotted line position, the upper end of the blank will be pulled away from the stop 10 to present its edge in the path of movement of a series of feed segments 22. The segments 22 are mounted in spaced relation on a shaft 23, and as the segments rotate in the direction of the arrow, their advancing hooked ends 22a simultaneously engage the edge of the blank that has been previously separated from the stack by operation of the picker 20.

The segments 22 cooperate with a set of segments 24, mounted in spaced relation on a shaft 25 parallel to the shaft 23, as best shown in Fig. 2. The lower segments 24 are in vertical alinement with the segments 22, and their forward ends 24a are adapted to register with the forward ends 22a of segments 22 as the segments rotate in opposite directions. Therefore, the edge of the deflected blank will be seized between the segments, and the blank withdrawn from the stack. As this withdrawal occurs, the trailing edge of the lowermost blank 2 is drawn past the trough 15, so that dry-sealing adhesive is applied between the end lugs 16 clear up to the edge of the blank with a wiping action, while the next lowermost blank progressively comes into contact with the trough 15, in readiness for the next withdrawal.

Each segment 24 provides a slot 26 near its forward end 24a, and the slots of all the segments 24 are connected to a suitable source of suction by a cross pipe 27, see Fig. 4. Therefore, as the leading edge of the blank being withdrawn leaves the bite between the segments 22 and 24, it is held on the segments 24 at the suction slots 26, and is wrapped around the segments 24 as the withdrawal progresses. As the leading edge of the withdrawn blank is carried around by the segments, the surface that was formerly uppermost in the stack is carried on the outside of the

segments, and so facing toward a second adhesive applying bar 28, the function of which will later appear.

It is evident from Fig. 1 that the peripheral length of each segment 24 is considerably less than the length of the shortest blank being handled, and the apparatus provides adjustable means for supporting each blank between the rear end of the segments 24 and the adhesive band A that is applied to the trailing end of the blank. To this end, guide segments 29 are mounted on the shaft 25 between the feed segments 24, with each segment 29 providing a groove 30, the purpose of which will later appear. The outside diameter of each segment 29 is less than the diameter of the feeding portion of each segment 24, so that stripping fingers 31 can enter between the segments 29 and the second adhesive applying bar 28, as shown in Fig. 6.

The several guide segments 29 are connected together by a tie rod 32, so that all the segments can be turned in unison on the shaft 25, and located in adjusted position by a set screw 33 passing through the hub of the center segment. Thus, the segments 29 can be angularly adjusted with respect to the forward ends 24a of the feed segments, so as to provide a series of spaced supports for the blank being withdrawn, extending from the rear ends of the segments 24 to a point adjacent the band A of moist adhesive that has just been applied to the blank. This prevents buckling of the blank as it is carried around on the segments 24, with the adhesive band A facing towards the segments 29, but entirely out of contact therewith.

As previously pointed out, a second adhesive applying bar 28 is located below the feed segments 24, and as best shown in Figs. 3 and 4, is similar to the first bar 13, in providing an adhesive trough 34 and suction slit 35 with end lugs 16a determining the effective length of the trough 34. The bar 28 has a number of stripping fingers 31 mounted thereon, which fingers overhang both the suction slit 35 and the adhesive trough 34. The under side of each finger 31 is cut away to provide a shoulder 36 just beyond the edge of the suction slit 35, thereby leaving a space between the fingers and the edges of the adhesive trough 34, sufficient to admit at least two blanks, see Fig. 10.

When the feed segments 24 carrying the leading edge of a blank approach the adhesive bar 28 as shown in Fig. 4, it is evident that the fingers 31 lie nearer the axis of the shaft 25 than does the approaching edge of the blank 2. Therefore, as the forward ends 24a of the segments sweep over the bar 28, the fingers 31 enter between the blank and the peripheries of the guide segments 29 which, as previously pointed out, are of less diameter than the big feed segments 24. This relation is shown diagrammatically in Fig. 6, wherein the different diameters of the segments 24 and 29 are shown with relation to the upper edge of the bar 28 and the stripping fingers 31.

As the fingers 31 pass over the leading edge of the moving blank, suction is released from the slots 26, so that the blank is readily stripped from the segments 24. As this occurs, further travel of the blank is arrested as its edge engages the shoulders 36 of fingers 31 which act as gauging stops to line up the edge of the blank with the suction slit 35 of the bar 28. As the segments 24 and 29 continue their rotation free of the stripped blank, preparatory for the next blank feed, the trailing edge of the blank with the ad-

hesive band A uppermost, swings downwardly toward a pair of spaced conveyor belts 37 that are driven slowly in the direction of the arrow by a mechanism hereafter described with reference to Fig. 11.

However, before the free end of this blank can reach the plane of the belts 37, its trailing edge is prevented from further downward movement by a blade 38 extending over the space between the belts, as shown in Fig. 3. This blade 38 is mounted on an arm 39 carrying one of a pair of rolls 40 adapted to be moved back and forth with respect to the belts 37. The opposite end of each arm 39 is mounted on a head 41, freely turnable on a pin 42 provided at the upper end of a lever 43 carried by a shaft 44 extending between the side frames 1. The roll arm 39 is adjustable within the head 41 through the provision of a slot 39a, so that the extreme positions occupied by each roll 40 can be adjusted longitudinally of the cooperating belt 37, in order to operate on blanks of different lengths, see Fig. 1.

Generally speaking, the setting of a roll 40 and its associated arm 39 is such that when the roll 40 occupies the retracted position of Fig. 4, the blade 38 is clear of the falling end of an approaching blank as carried by the segments 24. However, as the segments move past the bar 28 to cause stripping of a blank, as previously described, the roll 40 moves to the position of Fig. 5, wherein the blade 38 holds the end of the stripped blank above the belts 37, until the previously fed blank has been withdrawn from the bar 28 to cause the application of a second adhesive band B to the under side thereof that overlies the trough 34. In other words, as each blank is stripped from the segments 24 by the fingers 31, it is temporarily maintained out of contact with the bar 28 by the presence of the underlying end portion of the previously delivered blank, which is then pulled from under the blank that has just arrived, by cooperation between the rolls 40 and belts 37, as will next be described.

For purposes of illustration, let it be assumed that a blank is already in position, as shown in Fig. 4, with one end held in close contact with the trough 34 by suction along the slit 35, while its other end is supported between the belts 37, with the previously applied adhesive band A uppermost. Then, when the next blank is stripped from the segments 24, as shown in Fig. 5, and its trailing end swings downwardly, as indicated by the several dotted line positions, the blade 38 will be moved towards the bar 28 with the roll 40, to temporarily hold the end of the arriving blank away from the blank already on the belts 37.

Just after the arriving blank comes to rest against the stop shoulders 36, above the blank already in position, a series of clamping arms 45 mounted on a cross rod 46, are moved downward slightly, as indicated by the arrow in Fig. 5. Each arm 45 carries a rubber block 47, which engages the end of the uppermost blank between the fingers 31, so as to exert a frictional force to oppose removal of the blank that is so engaged. The rod 46 is rotatably supported at its ends by brackets 48 carried by the frame members, see Fig. 9, and an arm 49 mounted on the rod 46 carries a roll 50 bearing on a cam 51 rotatable with the segment shaft 25. The cam 51 is so timed as to turn the rod 46 into the position of Fig. 5, and thereby clamp the blanks beneath the fingers 31 before the roll 40 starts to

move from the position of Fig. 4 to the position of Fig. 5, as indicated in Fig. 14.

As best shown in Fig. 3, each roll 40 in its retracted position, is entirely clear of the side flaps 2a of the blank that is at the moment held at its end in engagement with the adhesive trough 34. Although the belts 37 are slowly moving away from the bar 28 underneath the flaps 2a, the suction along the slit 35 is quite sufficient to hold the blank in position against the relatively slight pull exerted by the upper surfaces of the belts alone. However, as the rolls 40 move into the position of Fig. 5 and thereby engage the flaps 2a, the downward pressure of the rolls 40 is sufficient to cause the flaps 2a to be carried along by the belts 37. Therefore, the lower blank is withdrawn from beneath the upper blank which is held by the frictional blocks 47 on the clamping arms 45, and an adhesive band B is applied to the under side of the trailing end thereof as the blank clears the trough 34, as indicated in Fig. 6. The upper blank thereupon takes the place of the blank being withdrawn, to keep the trough 34 covered at all times.

Since withdrawal of the lower blank from the bar 28 is followed by return movement of the rollers 40 to the right, the end of the blank that has just been stripped is freed from the blade 38 only after the advancing end of the underneath blank has reached a position where its adhesive band A is clear of the blank above. Therefore, the upper blank flattens out on the lower blank, with their ends in offset relation, so that the adhesive bands A are separated by a considerable space, which increases to the extent shown in Fig. 6, due to the continued pressure of the rolls 40 on the side flaps of the blank that has just been removed from the bar. By the time that the rolls 40 are again moved into the dotted line position to engage the flaps 2a of the second blank, a third blank has been stripped by the fingers 31, so that withdrawal of the trailing end of the second blank from the trough 34 to apply adhesive thereto, is accompanied by gripping of the third blank by the clamping arms 45.

As the above described cycle of operations is repeated for each revolution of the segment shaft 25, an assembly of overlapped blanks accumulates on the belts 37, as indicated in Figs. 7 and 8, with the adhesive bands A and B uniformly spaced from each other, so that there is no possibility of anything coming in contact with the moist adhesive while the blanks are supported between the belts 37 by their overlapped side flaps. It is evident from Fig. 8, that by the time the fifth blank has joined the assembly, the side flaps 2a of the first blank have come under the first of a series of traction rolls 52, forming part of a conveyor which carries the assembled blanks into a heating zone, where the moist adhesive bands A and B on opposite sides of the assembly are subjected to a drying action. These rolls 52 are all so mounted as to exert a pressure on the blank flaps as supported by the belts 37, so that the entire assembly of blanks moves along with the belts, with additional blanks being added to the assembly at intervals, each time that the rolls 40 move toward the adhesive bar 34 to engage the flaps of a blank then held in contact with the adhesive in the trough 34.

As best shown in Fig. 1, the adhesive drying means consists of hoods 53, arranged above and below the belts 37 and traction rolls 52, with each hood providing a suitable heating element 54,

spaced from a reflecting surface 55. As a result, heat is directed towards the spaced adhesive bands A and B from both sides of the assembled blanks, so that the adhesive is dried to its proper dry-sealing condition before the performance of various folding and gumming operations involved in the conversion of the blanks into complete envelopes. Obviously, other drying means may be employed in cooperation with the conveyor, and if desired, the adhesive applying bar 13 at the stack can be omitted, and ordinary dextrene gum applied by the bar 28 to the seal flaps of blanks for ordinary envelopes.

As previously pointed out, the stack-supporting posts 3 and 4 are adjustable to accommodate blanks of different sizes, and the conveyor mechanism is correspondingly adjustable, so that the belts 7 can be set just the right distance apart to support the side flaps of blanks of different widths. In Figs. 11, 12 and 13, the parts of the conveyor mechanism are shown separately from the adhesive applying devices previously described, and it is evident from Fig. 11, that the conveyor can be made of any desired length, in order to obtain the necessary drying of the adhesive as applied to the assembled blanks.

Referring now to Figs. 12 and 13, the upper portion of each belt 37 is supported by a rail 56 for the entire length of the conveyor, with the ends of the belt passing around pulleys 57 and 58. The rails 56 are mounted in parallel spaced relation on screw shafts 59 extending between the side frames 1, with each shaft 59 being oppositely threaded at 60 and 61, where it passes through brackets 62 secured to the under side of a rail 56. Consequently, when a shaft 59 is turned, the rails 56 move toward or away from each other, in order to vary the distance between the belts 37.

One shaft 59 extends beyond a frame member 1, where it provides a slot 63 for receiving a suitable handle whereby it may be turned, and in order to insure movement of the rails 56 in exact parallel relation, the screw shafts 59 are connected together for turning in unison. As shown in Fig. 11, the shafts 59 are connected together by sprockets 64 and a chain 65, so that close adjustment of the spacing between the rails 56 can be obtained at any time, in order to accommodate the belts 37 to the exact distance between the side flaps 2a of the assembled blanks that are conveyed thereby, as previously described.

Each front belt pulley 57 is slidably keyed to a shaft 66 extending between the frame members 1, and the shaft 66 is adapted to be continuously driven from the feed segment shaft 25 through a train of reduction gearing 67, best shown in Fig. 2, so that the pulleys 57 rotate at a much lower speed than do the segments 24. In order to cause the pulleys 57 and the belts 37 to move with the rails 56 when making an adjustment in the width of the conveyor, each rail bracket 62 provides wings 68 embracing a pulley 57, so that each pulley and the belt carried thereby is always in alignment with the associated rail. The rear pulleys 58 are not driven, and each pulley 58 is supported from the end of a rail 56 by a bracket 69, into which is threaded the rear screw shaft 59. Each pulley 58 is supported on a stud 70 that is adjustable within a slot 71 provided by the bracket 69, in order to adjust the tension of each belt 37.

The operating lever 43 for each arm 39 that carries a pull roll 40, provides a hub 72 that is

slidably keyed to the shaft 44 that passes freely through the conveyor below the rails 56. Each hub 72 provides a slot 73, in which is received a rail 56, so that when the rails 56 are adjusted by means of the screw shafts 59, the levers 43 are moved with the rails to maintain the rolls 40 in the same relative positions with respect to the belts 37, as previously described with reference to Fig. 3. In other words, any adjustment of the space between the rails 56 is accompanied by corresponding movement of the associated pulleys 57 and 58 and the belt 37 carried thereby, as well as of the lever 43, which pivotally supports the roll 40 that is depended upon to move each blank from the second adhesive applying station to the assembled blanks on the belts.

As best shown in Fig. 13, a series of traction rolls 52 are supported above each belt 37 by a bar 74 extending parallel to and above a rail 56. Each bar is supported at intervals along the conveyor by brackets 75, secured to the under side of a rail 56 and providing studs 76 extending inwardly so as to slightly overhang the associated rail. Each traction roll 52 is rotatably carried by an arm 77 pivotally mounted on a bar 74, and springs 78 acting on the arms 77 yieldably maintain the rolls 52 in engagement with the associated belts 37. Therefore, when the overlapped flaps 2a of an assembled series of envelope blanks are engaged by the traction rolls 52, the rolls exert sufficient pressure to maintain the flaps firmly in engagement with the slowly moving belts 37, so that the assembled envelopes are conveyed between the dryer hoods 53. The fact that one or more blank flaps are engaged by each roll 52, insures that the assembled blanks will travel along the conveyor without sagging in the space between the belts where the adhesive bands A and B are exposed to a drying action on opposite sides of the assembly.

Referring again to Fig. 2, the shaft 25 which carries the feed segments 24, is continuously driven from any suitable source of power, not shown, as by means of a sprocket 79. A pinion 61a forming part of the reduction gearing for driving the conveyor pulley shaft 66, is mounted on the shaft 25 adjacent the driving sprocket 79, so that the conveyor belts 37 are driven at a lineal speed considerably less than the peripheral speed of the segment 24. The shaft 25 also carries a gear 80, which is in mesh with a gear 81 mounted on the shaft 23 which carries the upper set of feed segments 22. The gears 80 and 81 have a one to one ratio, so that the segments 22 and 24 travel at the same speed, although in opposite directions of rotation.

The shaft 23 carries a cam 82 adjacent the gear 81, and this cam 82 is adapted to control pivotal movement of the suction picker 20. The picker 20 is turnable with the shaft 21 that is mounted on the rear side of the cross member 9, as indicated by the broken-away portion. The opposite end of the shaft 21 carries a lever 83, the lower end of which carries a roll 84 bearing on the cam 82. The upper end of the lever 83 is connected to a spring 85, which as best shown in Fig. 1, tends to hold the roll 84 in engagement with the surface of the cam 82.

With the roll 84 bearing on the high portion of the cam 82, as indicated in Fig. 14, the free end of the picker 20, shown in dotted lines, will be held in engagement with the lowermost blank 75 of the stack adjacent the stop 10, in position

to remove a blank. However, as the cam surface falls away from the roll 84, the picker 20 will be turned with the shaft 21 under the pull of spring 85 to flex the end of the blank away from the stop 10, due to suction, which at that time is applied to the picker. From the form of the cam 82 indicated in Fig. 14, it is evident that the picker 20 will be turned to separate a blank from the stack, just prior to the arrival of the forward ends 22a of segments 22 at the upper end of the stack.

As indicated above, suction is adapted to be applied to the picker 20, and to this end, a pipe 86 leads from one bearing 87 of the shaft 21, which is hollow. The other end of the pipe 86 is connected to a block 88 leading to a timing device 89 carried by the frame, and having a rotating element, not shown, turnable with the gear 81. The timing device 89 is so set that suction is applied to the picker 20 over substantially one half of a revolution of the shaft 23. As indicated by the arrows of Fig. 14, the suction starts substantially one quarter of a revolution in advance of the arrival of the forward ends 22a of the segments 22 at the stack, and is cut off substantially at the same moment that the leading edge of a blank being withdrawn enters the bite of the segments 22 and 24.

A second timing device 90 surrounds the shaft 25 and comprises a rotating element, not shown, turnable with the gear 80, whereby the source of suction is connected once during each revolution of shaft 25 to the cross pipe 27 that extends between the several feed segments 24, in communication with the several slots 26 adjacent the forward ends 24a of the segments. As indicated in Fig. 14, suction is applied to the cross pipe 27 through substantially one half a revolution of the shaft 25, so that suction is present at the slots 26, just before meeting the forward ends 22a of the segments 22. The suction applied to the segments 24 is broken just as the leading edge of the withdrawn blank reaches the stripping fingers 31, so that the blank is firmly held by the segments 24 until the stripping action begins. Thus the applications of suction to the picker 20 and to the segments 24, slightly overlap in point of time, just before a blank enters the bite between the segments 22 and 24.

As best shown in Figs. 2 and 14, the shaft 25 carries a cam 91 beyond the right-hand frame 1, with which cooperates a roll 92 carried by a lever 93, freely mounted on an end of the shaft 66 which drives the conveyor pulleys. The lever 93 is connected by a link 94 to a similar lever 95, turnable with the shaft 44 carrying the arms 43 which control the position of the rolls 40, as indicated in dotted lines. The cam 91 is so timed that the rolls 40 are adapted to move in quickly to the position shown in Fig. 5, after the clamping arms 45 have operated to engage the leading edge of the blank that has just arrived at the second adhesive applying bar 28. As the lowermost blank at the bar is pulled out, due to the pressure of the rolls 40 on the belts 37, the cam 91 retracts the rolls 40 to the position of Figs. 6 and 7 where they remain an appreciable period, equivalent to substantially one half of a revolution of the shaft 25.

As previously pointed out, the shaft 25 also carries a cam 51 for controlling the clamping arms 45, the cam 51 being indicated in dotted lines in Fig. 14. From this showing it is evident that the timing of the cams 91 and 51 is such

that the clamping arms 45 will be turned downwardly into the position of Fig. 5, before the rolls 40 move in, and that this clamping pressure will be maintained on the blank just stripped until the lowermost blank on the bar 28 has been completely cleared of the trough 34, as shown in Fig. 6.

From the description of the operation of the machine thus far, it is evident that a blank must always be in engagement with either of the adhesive applying bars 13 or 28, in order to prevent adhesive from overflowing the troughs 15 and 34. In the case of the first adhesive applying bar 13, this condition is always insured as long as there are any blanks in the stack, due to the fact that as the lowermost blank is withdrawn, the blank next above will naturally come into position with its edge held by the suction slit 17.

As regards the second adhesive applying station, it is obvious that the above described essential conditions will be maintained as long as a blank is stripped by the fingers 31 from the segments 24, for each revolution of the shaft 25. However, it is evident that should the suction picker 20 fail to remove a blank from the stack as it turns with the shaft 21, a condition will thereafter arise, wherein the removal of the blank last delivered from the bar 28 will leave the trough 34 uncovered. As this would be undesirable, due to possible overflowing of the adhesive, the invention contemplates means for automatically preventing movement of the rollers 40 to the blank withdrawing position of Fig. 5, should the picker 20 fail to deliver a blank to the feed segments 22 and 24.

To this end, the shaft 44, which carries the arms 43, also carries a stop arm 96, which is located outside one of the side frames 1, as shown in Fig. 11, opposite to the lever 95. This stop arm 96 swings back and forth as the shaft 44 is turned first in one direction and then the other by the cam 91, to impart a reciprocatory movement to the rolls 40. In so moving, the arm 96 sweeps past the end of a cylinder 97, in which a plunger 98 is movable by means of a piston 99, as indicated at the broken-away portion of the frame 1 in Fig. 11.

The piston 99 is hollow and a spring 100 is adapted to urge the piston 99 outwardly to a position wherein the end of the plunger 98 projects beyond the cylinder 97 into the path of movement of the stop arm 96, as indicated in dotted lines. The opposite end of the cylinder 97 is connected by a pipe 101 to an opening 102 communicating with the inside of the suction picker 20, see Fig. 14. When suction is applied to the picker 20, the plunger 98 will be withdrawn out of the path of movement of the arm 96, as shown in full lines in Fig. 11, due to the admission of air at atmospheric pressure through a port 103 provided at the opposite end of the cylinder 97.

During the normal operation of the mechanism, suction will be applied to the cylinder 97 throughout the entire period that suction is applied to the picker 20, so that the end of the plunger 98 is retracted when the stop arm 96 moves past the cylinder as the shaft 44 turns to move the rolls 40 from the position of Fig. 4 to the position of Fig. 5. At this particular moment, two blanks are in position over the bar 28, and the picker 20 has already swung away from the stack to flex the end of the lowermost blank of the stack into a position where its edge will be seized by the advancing forward ends 22a

of the segments 22. However, should the picker 20 fail to pull a blank away from the stack as it so moves, the end of the picker will be open, so there will be no suction at the opening 102 leading to the pipe 101. When this occurs, suction is no longer effective in the cylinder 97 to retract the plunger 98, with the result that the spring 100 pressing on the piston 99, forces the plunger out into the path of movement of the stop arm 96.

Assuming that the lever 95 and arm 96 occupy the dotted line positions of Fig. 14 upon the occurrence of a failure in the blank feed, as described above, it is evident that the shaft 44 will be prevented from turning in a counter clockwise direction, by reason of the engagement of the arm 96 with the projecting end of the plunger 98. Therefore, when the low portion of the cam 91 comes opposite the roll 92 on the lever 93, as shown in full lines, the roll 92 is unable to follow the face of the cam under the pull of the spring 93a, and there is no movement imparted to the pull rolls 40 in the direction of the bar 28 to cause withdrawal of the lowermost blank from beneath the stripping fingers 31. In this way, the withdrawal of the blank from the bar 28 is automatically prevented until another blank has actually been withdrawn from the stack by the suction picker, thereby insuring that at all times a blank will be in position over the bar 28, so as to be in engagement with the adhesive applying trough 34.

From the foregoing, it is apparent that by the present invention there is provided an improved method and apparatus for applying dry-sealing adhesive to different and separated areas of envelope blanks, followed by drying of the adhesive from opposite sides of an assembly of overlapping blanks, with the separate adhesive areas positively maintained in spaced relation, so that stringing or edge sticking of adjacent blanks is entirely eliminated. In carrying out the invention, each blank is successively moved in different planes, so as to cause the application of the adhesive with a wiping action, to what constitutes the trailing edge of the blank in each separate movement. In this way, the troublesome problems heretofore encountered in the application of dry-sealing adhesive, are successfully solved, owing to the fact that each application of adhesive to a given blank, is made entirely independently of the application of adhesive to other blanks, and that all the adhesive applications are maintained entirely separate during the drying thereof.

I claim:

1. An improved method of applying adhesive to envelope blanks, which consists in first withdrawing a blank from a supply of blanks while engaged with a supply of adhesive, said withdrawal being accompanied by the application of adhesive to the trailing edge of the blank on one side only, then presenting the leading edge of the blank to a second adhesive supply followed by withdrawal of the blank from said second supply, accompanied by application of the adhesive to the trailing edge of the blank on the opposite side, as regards its second withdrawal.

2. The improved method of applying adhesive to envelope blanks, which consists in first withdrawing a blank from a supply of blanks while engaged with a supply of adhesive, with said withdrawal being accompanied by the application of adhesive to the trailing edge of the blank, then

presenting the leading edge of the blank to a second adhesive supply followed by withdrawal of the blank from said second supply, accompanied by application of the adhesive to the trailing edge of the blank as regards its second withdrawal, and finally in supporting and conveying said blank while subjecting the applications of adhesive to a drying action from opposite sides of the blank.

3. Apparatus for applying adhesive to blanks, comprising in combination, a supply of adhesive, means for supporting a stack of blanks, with the lowermost blank of the stack in engagement with said adhesive supply, a second supply of adhesive, means for maintaining a blank in engagement with said second adhesive supply, means for removing a blank from the first adhesive supply and delivering it to the second, and means operated in timed relation with said first blank-removal means for removing a previously delivered blank from said second adhesive supply.

4. Apparatus for applying adhesive to blanks, comprising in combination, a supply of adhesive, means for supporting a stack of blanks, with the lowermost blank of the stack in engagement with said adhesive supply, a second supply of adhesive, means for maintaining a blank in engagement with said second adhesive supply, means for withdrawing a blank from the stack to cause the application of adhesive from the first supply to the trailing edge thereof, means for delivering said blank to the second adhesive supply, and means for causing the removal of a previously delivered blank from said second supply to apply adhesive to the trailing edge thereof.

5. Apparatus for applying dry-sealing adhesive to blanks, comprising in combination, a supply of adhesive, means for supporting a stack of blanks, with the lowermost blank of the stack in engagement with said adhesive supply, a second supply of adhesive, means for maintaining a blank in engagement with said second adhesive supply, means for withdrawing a blank from the stack to cause the application of adhesive from the first supply to the trailing edge thereof, means for delivering said blank to the second adhesive supply, means for causing the removal of a previously delivered blank from said second supply to apply adhesive to the trailing edge thereof, and means for supporting a blank as withdrawn from the second adhesive supply, with the applications of adhesive at different edges thereof exposed to a drying action.

6. Apparatus for applying adhesive to blanks, comprising in combination a supply of adhesive, means for supporting a stack of blanks, with the lowermost blank of the stack in engagement with said adhesive supply, a second supply of adhesive, means for maintaining a blank in engagement with said second adhesive supply, means for withdrawing a blank from the stack and the first adhesive supply and delivering it to the second adhesive supply, means for causing the removal of a blank from the second adhesive supply, and means for preventing the withdrawal of a blank from the second adhesive supply, in advance of the delivery of a blank from the first adhesive supply.

7. Apparatus of the class described, comprising in combination, separate sources of adhesive supply, means for maintaining separate blanks in engagement with each such supply, means for transferring a blank from one adhesive supply to the other, means for causing the removal of a

blank from the second-named supply, and means for preventing functioning of the blank removing means, upon failure of the blank transfer means.

8. In apparatus of the class described, a bar providing an open trough for receiving liquid adhesive, means for positioning a blank of said bar with a portion thereof engaging said trough along a zone parallel to one edge, but offset therefrom, suction means acting on the edge of the blank to maintain it in engagement with said adhesive trough, and means for withdrawing said blank from said bar to cause the application of adhesive up to said edge.

9. In apparatus of the class described, a member providing an open trough for receiving a liquid adhesive, means for positioning a blank on said member with a portion thereof engaging said trough along a zone parallel to one edge but offset therefrom, a conveyor for supporting a portion of said blank beyond said member, without imparting movement thereto, and means cooperating with said conveyor to withdraw said blank from said trough and cause the application of adhesive up to said blank edge.

10. In apparatus of the class described, a member providing an open trough for receiving a liquid adhesive, means for positioning a blank on said member with a portion thereof engaging said trough along a zone parallel to one edge but offset therefrom, a conveyor for supporting a portion of said blank beyond said member, without imparting movement thereto, and means cooperating with said conveyor to withdraw said blank from said trough and cause the application of adhesive up to said blank edge, said conveyor being adapted to engage said blank only outside of the zone of application of the adhesive.

11. In apparatus of the class described, a member providing an open trough for receiving a liquid adhesive, means for positioning a blank on said member with a portion thereof engaging said trough along a zone parallel to one edge but offset therefrom, a conveyor for supporting a portion of said blank beyond said member, without imparting movement thereto, and means cooperating with said conveyor to withdraw said blank from said trough and cause the application of adhesive up to said blank edge, said trough being adjustable between its ends to control the length of the adhesive band applied to said blank, and said conveyor being adjustable in width, so as to engage said blank only outside of the extremities of the adhesive band.

12. In apparatus of the class described, a member providing an open trough for receiving liquid adhesive, means for positioning a blank on said member, with an end portion thereof engaging said trough along a zone parallel to one edge but offset therefrom, said blank providing side flaps extending beyond its zone of engagement with said member, spaced conveyor belts adapted to engage said side flaps, and means cooperating with said belts and side flaps to cause the withdrawal of said blank from said trough accompanied by the application of adhesive from said trough in a band extending up to the trailing edge of the blank.

13. In apparatus of the class described, a member providing an open trough for receiving liquid adhesive, means for positioning a blank on said member, with an end portion thereof engaging said trough along a zone parallel to one edge but offset therefrom, said blank providing side flaps extending beyond its zone of engagement with said member, spaced conveyor belts adapted to

engage said side flaps, and means cooperating with said belts and side flaps to cause the withdrawal of said blank from said trough accompanied by the application of adhesive from said trough in a band extending up to the trailing edge of the blank, said adhesive trough being adjustable in length to accommodate blanks of different widths, and said belts being relatively adjustable to vary the space therebetween for engaging the side flaps of blanks of different widths.

14. In apparatus of the class described, a member providing an open trough for receiving liquid adhesive, means for delivering a blank edgewise to said member, means for stripping said blank from said delivery means, and positioning the blank on said member with an end portion thereof engaging said trough along a zone parallel to one edge but offset therefrom, and suction means acting on the edge of the blank to maintain it in engagement with said adhesive trough, whereby withdrawal of said blank from said bar causes the application of adhesive up to said edge.

15. In apparatus of the class described, a member providing an open trough for receiving liquid adhesive, means for delivering a blank edgewise to said member, means for stripping said blank from said delivery means, and positioning the blank on said member with an end portion thereof engaging said trough along a zone parallel to one edge but offset therefrom, suction means acting on the edge of the blank to maintain it in engagement with said adhesive trough, whereby withdrawal of said blank from said bar causes the application of adhesive up to said edge, and means for maintaining a second blank in register with the trough above the blank being withdrawn, whereby withdrawal of the lowermost blank is accompanied by progressive engagement of the upper blank with said suction means and trough.

16. In apparatus of the class described, a member providing an open trough for receiving liquid adhesive, means for successively delivering blanks edgewise to said member, means for stripping blanks from said delivery means to position blanks in overlying relation above said member, with a portion of the lowermost blank engaging said trough along a zone parallel to one edge, but offset therefrom, means for withdrawing said blank from said trough to cause the application of adhesive up to its edge, and means co-operating with said member to prevent the uppermost blank from being withdrawn.

17. In apparatus of the class described, a member providing an open trough for receiving liquid adhesive, means for successively delivering blanks edgewise to said member, means for stripping blanks from said delivery means to position blanks in overlying relation above said member, with a portion of the lowermost blank engaging said trough along a zone parallel to one edge, but offset therefrom, means for withdrawing said lowermost blank from said trough to cause the application of adhesive up to its edge, and means for maintaining the edge of the uppermost blank in register with said trough during withdrawal of the lowermost blank, whereby said withdrawal is accompanied by progressive engagement of the uppermost blank with said trough.

18. In apparatus of the class described, a member providing an open trough for receiving liquid adhesive, means for successively delivering blanks edgewise to said member, means for stripping blanks from said delivery means to position blanks in overlying relation above said member, with a portion of the lowermost blank engaging

said trough along a zone parallel to one edge, but offset therefrom, means for withdrawing said lowermost blank from said trough to cause the application of adhesive up to its edge, conveying means for partially supporting only the lower one of two overlying blanks while in register with said bar, without imparting movement thereto, means cooperating with said conveying means to cause the withdrawal of said blank from said trough, accompanied by the application of adhesive up to its edge, and means operating on the uppermost blank to hold it in register with said trough and out of contact with said conveying means, while said withdrawal is being accomplished.

19. An improved method of applying dry-sealing adhesive to envelope blanks, which consists in supporting a blank with an edge portion thereof held in engagement with a supply of dry-sealing adhesive extending parallel to said blank edge portion, moving a second blank into overlying relation to the first blank with an edge portion thereof alined with the edge portion of the first

5 blank, and then withdrawing said first blank from said adhesive supply to cause the application of adhesive up to the trailing edge thereof, accompanied by the progressive engagement of the alined edge portion of said second blank with the adhesive supply, as the first blank is withdrawn.

10 20 20 An improved method of applying dry-sealing adhesive to envelope blanks, which consists in supporting a blank with an edge portion thereof held in engagement with a supply of dry-sealing adhesive extending parallel to said blank edge portion, moving a second blank into overlying relation to the first blank with an edge portion thereof alined with the edge portion of the first blank, and then withdrawing said first blank from said adhesive supply to cause the application of adhesive up to the trailing edge thereof, while maintaining alinement of the edge portion of said second blank with the adhesive supply, as the first blank is withdrawn.

VINCENT E. HEYWOOD.
